UNITED STATES PATENT OFFICE.

HENRY C. LOUDERMILCH, OF FISHERVILLE, PENNSYLVANIA.

COLLAR-FASTENER.

SPECIFICATION forming part of Letters Patent No. 669,931, dated March 12, 1901.

Application filed November 18, 1897. Serial No. 658,452. (No model.)

To all whom it may concern:

Be it known that I, HENRY C. LOUDERMILCH, a citizen of the United States, residing at Fisherville, in the county of Dauphin 5 and State of Pennsylvania, and whose post-office address is Enders, Dauphin county, Pennsylvania, have invented a new and useful Improvement in Horse-Collars, of which the following is a specification.

10 My invention relates to horse-collars, and has for its object to generally improve their construction and operation and to furnish a horse-collar with improved means for opening, closing, and securing it at the bottom.

15 With this object in view my invention consists in the improved construction, arrangement, and combination of parts hereinafter fully described and afterward specifically pointed out in the appended claim.

20 In order to enable others skilled in the art to which my invention most nearly appertains to make and use the same, I will now proceed to describe its construction and operation, reference being had to the accompanying drawings, forming part of this specification, in which—

Figure 1 is a view in front elevation, partly in section, illustrating a horse-collar equipped with my improvements. Fig. 2 is a detail 30 sectional view of the same on the line 2 2 of Fig. 1. Fig. 3 is a perspective view of the spring-plates and their opening mechanism detached from the collar. Fig. 4 is a detail perspective view of the arrow-head catch-bar 35 detached. Fig. 5 is a fragmentary detail view, in front elevation, of the lower part of the collar with the joint closed and covered by the metallic sleeve.

Like letters of reference mark the same 40 parts wherever they occur in the various figures of the drawings.

Referring to the drawings by letters, A is an ordinary stuffed collar closed and padded at the top, as at B, and open at its lower end, 45 as at C, the meeting ends of the collar being marked E. Secured to the end D is a metallic sleeve F, outwardly shaped to correspond with the shape of the collar, and within this sleeve are secured, by means of rivets G, two spring-plates H, each of which is provided at its outer end with a latch-hook I, 50 projecting inwardly and beveled on its outer

end, as at I'. The rivets G pass through openings in the rear ends of the plates and through a separating-block J, by which means the 55 plates and separating-block are rigidly secured in the joint-covering sleeve F. The ends of plates are substantially straight and parallel, while the intermediate portion of each of them is bent or curved inward, which 60 permits of the rear ends fitting between the ends of the block J and the sides of the sleeve F, thereby holding them rigidly in position without additional fastening means and firmly securing them against longitudinal or 65 forward movement. The block and rivets are located at such a distance from the rear end of the sleeve F as to leave room for the insertion of the end D of the collar, where it is secured by suitable rivets or fasteners. The 70 opposite end E of the collar is provided with a metallic cap K, of the proper shape to slip into the open end of the sleeve F, and an arrow-head catch-bar L projects beyond the end E a sufficient distance to pass in between 75 the latch heads or hooks of the spring-plates H when the ends are brought together. This arrow-head catch-bar L is secured to the end E of the collar by long rivets M, which pass through the metallic cap K and the bar and 80 hold it rigidly in proper position to engage the latch-hooks I when the two ends are brought together.

A shaft or stem N is swiveled in the sleeve F and carries an elliptic-shaped head O between the two spring-plates H, a handle P being provided on the outer end of the shaft N outside of the sleeve F, whereby the shaft and its head may be easily turned.

The operation of my invention may be described as follows: Supposing the ends D and E of the collar to be separated and the handle being turned to bring the longest diameter of the elliptical head O in line with the spring-plates H and as a consequence these 95 plates being in their normal closed position, the collar may be closed and fastened by simply pressing the two ends together, causing the arrow-head L' of the catch-bar L to pass between the latch-hooks I of the spring-plates H, 100 which will close upon the arrow-head as soon as it has passed in beyond the inner edge of the hook, thus securely holding the two ends of the collar together. To open the collar, it is

only necessary to turn the handle P at right angles to the position just described, which will bring the longest diameter of the elliptic head O at right angles to the length of the 5 spring-plates H and separate those plates, the head O acting as a cam for this purpose and the latch hooks or heads I of the plates being pressed far enough apart by this operation to permit of the withdrawal of the arrow-head L' of the catch-bar L. By turning the handle P to bring the elliptical head O to its original position, with its longest diameter in line with the length of the plates H, the collar will be left ready to be snapped together, 15 when desired.

From the foregoing it will be obvious that I have provided simple and reliable means for effectually closing and holding the open lower ends of a collar together, which means are 20 within easy reach of any person desiring to harness the horse, from a tall man to a small boy, thus obviating the difficulty experienced with collars which open at the top when a short man or boy attempts to harness a horse, 25 especially a restive or spirited one.

While I have illustrated and described what I consider to be efficient means for carrying out my invention, I do not wish to be understood as limiting myself to the exact details 30 of construction and arrangement shown and described, but hold that any slight changes or variations, such as might suggest them-

35
selves to the ordinary mechanic, would properly fall within the limit and scope of my invention.

Having thus fully described my invention, what I claim as new, and desire to secure by Letters Patent of the United States, is—

In combination with a horse-collar, open at the bottom, of a sleeve on each end, one of 40 which is closed and smaller than and adapted to be telescoped into the other one, a perforated block in the larger one adjacent to the end of the collar, two springs, the ends of which are substantially parallel with each 45 other and the intermediate portion is curved inwardly, the forward ends of the springs being each provided with an inwardly-projecting inclined latch-head, and the rear ends being perforated and fitting between the ends 50 of the block and the sleeve, the plates and the block, an arrow-head catch projecting beyond the closed end of the smaller sleeve in position to engage with the spring-latch heads, and a shaft 55 journaled in the larger sleeve, the inner end of which is provided with an elliptical head between the forward ends of the springs and the outer end is provided with a handle for rotating it, substantially as described.

HENRY C. LOUDERMILCH.
